UNITED STATES PATENT OFFICE

171,836

AUTOMOBILE HOOD

Harry T. Bannister, Huntington Woods, Mich.,
assignor to Chrysler Corporation, Highland
Park, Mich., a corporation of Delaware

Application June 11, 1952, Serial No. 20,129

Term of patent 7 years

(Cl. D14—18)

To all whom it may concern:

Be it known that I, Harry T. Bannister, a citizen of the United States, residing in the city of Huntington Woods, county of Oakland, and State of Michigan, have invented a new, original, and ornamental Design for an Automobile Hood, of which the following is a specification, reference being had to the accompanying drawings, forming part thereof, in which:

Fig. 1 is a side elevational view of an automobile hood showing my novel design;

Fig. 2 is a top plan view thereof;

Fig. 3 is a front elevational view thereof; and

Figs. 4, 5, 6 and 7 are sectional views taken on the lines 4—4, 5—5, 6—6, and 7—7 respectively of Fig. 2.

The characteristic features of my design reside in the portions shown by means of full lines in the drawing.

I claim:

The ornamental design for an automobile hood, substantially as shown and described.

HARRY T. BANNISTER.
